(57) **CLAIM**

(21) Appl. No.: **29/161,408**

The ornamental design for an apparatus for treating an item during travel of the item along a spiral trough, as shown and described.

(22) Filed: **May 29, 2002**

DESCRIPTION

(60) Division of application No. 29/147,842, filed on Sep. 6, 2001, now Pat. No. Des. 462,369, which is a continuation-in-part of application No. 09/360,755, filed on Jul. 26, 1999, now abandoned.

FIG. 1 is a front elevational view of the apparatus for treating an item during travel of the item along a spiral trough showing the design of the invention;

FIG. 2 is a top plan view thereof;

FIG. 3 is a right side elevational view thereof;

FIG. 4 is a left side elevational view thereof;

FIG. 5 is a rear view thereof;

FIG. 6 is a bottom plan view thereof; and,

FIG. 7 is a bottom plan view of a second embodiment of the bottom thereof, the front, top, right side, left side, and rear views for this second embodiment are the same as shown in FIGS. 1-5.
